J. O. HOLMBERG.
COMBINATION DOORKNOB.
APPLICATION FILED MAY 5, 1921.

Patented Nov. 7, 1922.

UNITED STATES PATENT OFFICE.

JOHAN OSKAR HOLMBERG, OF QUINCY, MASSACHUSETTS.

COMBINATION DOORKNOB.

Application filed May 5, 1921. Serial No. 466,893.

To all whom it may concern:

Be it known that I, JOHAN OSKAR HOLMBERG, a citizen of the United States, residing in Quincy, in the county of Norfolk and State of Massachusetts, have invented an Improvement in Combination Doorknobs, of which the following description, in connection with the accompanying drawings, is a specification, like characters 10 on the drawings representing like parts.

This invention relates to a combination door knob especially designed and adapted for use with the spindle of the ordinary door lock, now commonly used on the doors 15 of dwelling houses, and other buildings.

The invention has for its object to provide the ordinary lock for doors with a combination knob, by which the ordinary lock can be converted in effect into a combination 20 lock by merely replacing the spindle and one of the door knobs now commonly used, with my improved spindle and door knob, which is constructed and arranged so as to enable the occupant of the house or other building 25 to change the combination at his pleasure and in a minimum time.

The invention further has for its object to provide an inexpensive construction of combination door knob, whereby the change 30 from a simple lock to a combination lock may be effected at a minimum cost.

The particular features of the invention will be pointed out in the claims at the end 35 of this specification.

Fig. 1 represents a portion of a door provided with a lock having a combination door knob embodying this invention, the latter being shown in section, taken on the line 1-1, Fig. 7.

Figs. 2, 3, 4, 5 and 6, details of the stationary members of the combination door knob shown in Fig. 1.

Fig. 7, a cross section on the line 7-7, Fig. 1, with parts omitted.

Fig. 8, a cross section on the line 8-8, and

Figs. 9 and 10, details of the movable and stationary members of the knob, to illustrate the relations thereof.

Referring to the drawing, *a* represents a door, provided with a lock *b* of normal or usual construction, having a bolt or catch *c* which is operated by a spindle *d* in the usual manner.

The spindle *d* is extended through the lock *b* and on one side of the door *a* is

provided with a knob 10 of usual construction, and on the other side of the door, which may be considered the outside, said spindle has mounted on it a combination 60 knob identified as a unit by the letter *e*.

In the present instance, one construction of combination knob embodying this invention is herein shown, and consists of a plurality of concentrically arranged hollow 65 members or sleeves, herein shown as four in number and marked 20, 21, 22, 23, Fig. 1, which cooperate with a like number of rings or members 24, 25, 26, 27, which may be designated the stationary members of 70 the knob, while the sleeves 20, 21, 22, 23 may be designated the movable members.

The members 24, 25, 26, 27 are concentrically arranged and mounted upon a hub 30 having a square or other angular opening or bore through which the spindle *d* is passed. The members 24, 25, 26, 27 are nested together as shown in Fig. 1 and the outside member 27 is soldered or otherwise fastened directly to a flange 31 on the hub 80 75 30. The members 24, 25 and 26 are not fastened to the flange 31 and are capable of being independently turned on the hub 30 to position them with respect to one another so as to require a particular or definite 85 positioning of the movable members or sleeves 20, 21, 22 before the spindle *d* can be turned by means of the combination knob. Each stationary member 24, 25, 26, 27 is provided with a projection or tongue 34, see 90 Figs. 5, 9 and 10, and each movable member 20, 21, 22, 23 is provided with a recess 35 into which the tongue cooperating with it is designed to enter and thereby couple the movable and stationary sleeve members 95 together.

Each of the members or rings 24, 25, 26 is provided with a plurality of holes 37, see Fig. 6, preferably twelve in number, and the outside ring or member 27 is provided 100 with two holes 38 located diametrically opposite. The rings 24, 25 and 26 are designed to be turned so as to place their projections or lugs 34 in the desired or selected position with relation to a zero or 105 starting point on the outside ring 27; and when so positioned the movable rings 24, 25 and 26 are rendered stationary by means of a pin 39 which is extended through the holes 38 in the outside ring 27 and through 110 holes 37 of the movable rings 24, 25 and 26 which are in alignment with the holes in

the ring 27, and also through holes in the spindle d and hub 30, as represented in Figs. 1 and 10. The holes 37 in the movable rings 24, 25 and 26 may be numbered from 1 to 5 12, and one of the holes in the stationary ring 27 may be numbered zero. The rings 24, 25 and 26 are rotated or turned on the hub 30, so that holes of different numbers may be brought into alignment with the 10 zero hole in the ring 27, and thereby establish a given combination. To illustrate, let it be supposed that the hole No. 3 in ring 26, hole No. 5 in ring 25 and hole No. 9 in ring 24, are brought into alignment 15 with the zero hole in ring 27, and that when so positioned, the pin 39 is inserted through said holes. In this case the projections 34 on these rings are arranged out of line with each other after the manner represented in 20 Fig. 5, and the knob is set for the combination 3, 5, 9. When the combination is thus established, it becomes necessary that the notches 35 in the sleeves 20, 21, 22 of the knob be brought into alignment with the 25 lugs on the stationary rings 24, 25, 26.

To effect this result, the operator must first turn the sleeves 20, 21, 22 back to the zero position, and to establish each of the sleeves in the zero position, each sleeve is 30 provided with a stop, which may be in the form of a pin 40, see Fig. 8, which cooperates with the end of a spring 41 having a projection or pawl 42 suitably shaped to engage one of a plurality of teeth or notches 43 on the sleeve. In the present instance each of the sleeves 20, 21, 22 is provided with 12 teeth or notches 43 corresponding to the holes 37 in the rings 24, 25, 26. Normally the ends of the sleeves 20, 21, 22 bear against 35 the ends of one or more of the lugs or projections 34 on the rings, see Fig. 10, and these sleeves are free to be turned or rotated without effecting rotation of the rings 24, 25, 26 and spindle d , and consequently without unlocking the door. Therefore a person who 40 does not know the combination can turn the knob e indefinitely without unlocking the door. A person having knowledge of the combination can quickly and easily unlock 45 the door by proceeding in the following manner. He first turns all the sleeves 20, 21, 22 back to zero position. He then turns the sleeve 20 the distance of three teeth, which is made known by three clicks of the pawl 42 50 cooperating with it. He then turns sleeves 20 and 21 the distance of five teeth, and then turns the sleeves 20, 21 and 22 the distance of nine teeth. In this manner, the notches 35 in the sleeves 20, 21, 22 are brought into alignment with the lugs 34 on their cooperating 55 rings 24, 25, 26. He then turns the knob as a whole by turning the sleeve 23 until the notch 35 in the latter is brought into alignment with the lug 34 on the ring 27, whereupon, all the sleeves as a unit are moved 60

lengthwise on the spindle from the position shown in Fig. 10 into that shown in Fig. 1, which causes the lugs 34 to enter the notches 35, and thereby couples the combination knob with the spindle, so that the latter can 70 be turned to throw the bolt or catch c and unlock the door.

The sleeves 20, 21, 22, 23 are moved lengthwise on the spindle to couple them with the latter, by helical spring 45, see Fig. 1. The 75 spring 45 bears at one end against a washer 46 and at its other end against a washer 47 which engages balls 48 in a raceway 49 which bears against a partition wall 50 on the sleeve 20, said wall having a square hole for 80 the passage of the square spindle and elongations 51 of said hole for the passage of a key or pin 52 extended through the spindle at one end of the hub 30, which has cooperating, with its other end a pin 53 by 85 means of which and the pin 52, the hub 30 is properly positioned on the spindle. To facilitate turning of the sleeves, it is preferred to provide the same with heads 54, 55, 56, 57 and to interpose between said 90 heads anti-friction balls 58. The pin 39 is loosely inserted through the stationary members 24 to 27 inclusive and is retained in position by a sleeve 70 loosely mounted on the outside ring 27 and preferably extended over 95 upon the sleeve 23 and abutting against a collar or flange 71 on the latter.

If it should be desired to change the combination, the screw 60 and knob 10 are removed from the spindle d , which latter is 100 then free to be withdrawn from the lock. The operator then slides the sleeve 70 away from the sleeve 23 to uncover the pin 53 and the pin 39. He then removes the pin 53 and turns the spindle so that the pin 39 may 105 drop out from the holes in the rings. This leaves the hub 30 and rings 24, 25, 26, 27 free to be moved on the spindle into a position where the rings 24, 25, 26 are accessible for turning, so that a new series of numbers may be brought into alignment with the zero hole in the outside ring 27. For instance, the ring 24 may be turned to bring its hole 4 into alignment, the ring 25 its hole 5, and the ring 26 its hole 6, after which the pin 39 110 is restored to lock the rings against turning. Thus a new combination of 4, 5, 6 is established. The hub 30 is then restored to its proper position and secured therein by the pin 53 and the sleeve 70 is again slid forward against the collar 71, after which the spindle is inserted through the lock, and the knob 10 secured by the screw 60, thereby placing the lock in condition to be operated when the combination knob is properly manipulated.

From the above description, it will be seen that the lock of the ordinary door can be converted into a combination lock by substituting for the spindle and one knob, the 115

spindle *d* and the combination knob *e*, using the other knob 10 of the door.

One embodiment of the invention is herein shown, but it is not desired to limit the invention to the particular construction shown.

Claims:

1. The combination with a lock provided with a bolt operating spindle, of a combination knob mounted on said spindle and comprising a plurality of sleeves concentrically arranged and independently rotatable, ring members mounted on said spindle and capable of being adjusted thereon into different positions, means for securing said ring members to said spindle in their adjusted position, and means for coupling said sleeves with said ring members to render said sleeves fast on said spindle.

2. The combination with a lock provided with a bolt operating spindle, of a combination knob mounted on said spindle and comprising a plurality of sleeves concentrically arranged and independently rotatable, a hub mounted on said spindle to rotate therewith, a plurality of ring members mounted on said hub and capable of being adjusted thereon, means for securing said ring members in their adjusted position, and means for coupling said sleeves with said ring members to render said sleeves fast on said spindle.

3. The combination with a lock provided with a bolt operating spindle, of a combination knob mounted on said spindle and comprising a plurality of sleeves concentrically arranged and independently rotatable, a hub mounted on said spindle to rotate therewith, a plurality of ring members having holes circumferentially arranged and capable of registering with one another, and with a hole in said spindle and hub, a device extended through predetermined holes in said ring members and through the holes in said spindle and hub, means for positioning said hub on said spindle, and means for coupling the said sleeves with said ring members.

4. A combination knob for the spindle of a lock comprising a plurality of sleeves of

different diameters concentrically arranged and independently rotatable and capable of being mounted on said spindle to move longitudinally thereon, a plurality of ring members nested together and of different diameters corresponding to the diameters of said sleeves and capable of being adjusted on said spindle and of being rendered stationary thereon in their adjusted positions, and means for coupling the said sleeves with said ring members by longitudinal movement of said sleeves on said spindle.

5. A combination knob for the spindle of a lock, comprising a plurality of sleeves concentrically arranged, independently rotatable, and having enlarged heads on the exterior of the sleeves, a plurality of cooperating ring members concentrically arranged and capable of being adjusted into different positions and of being rendered stationary in said positions, means for coupling the rotatable members with said stationary members and means for automatically moving said sleeves longitudinally for coupling said sleeves with said ring members in their stationary position.

6. The combination with the spindle of a lock, of a combination knob mounted on said spindle and comprising a plurality of members of different diameters nested together and normally free to be rotated by hand and capable of being moved longitudinally on said spindle, and a plurality of stationary members of different diameters nested together and fast on said spindle and with which the first mentioned rotatable members co-operate, and means for coupling the rotatable members with said stationary members when said rotatable members are turned on said spindle into a predetermined relation to said stationary members to permit the rotatable members to be moved longitudinally on said spindle.

In testimony whereof, I have signed my name to this specification.

JOHAN OSKAR HOLMBERG.
